US00D645529S

(12) United States Design Patent
Felker et al.

(10) Patent No.: US D645,529 S
(45) Date of Patent:  Sep. 20, 2011

(54) GOLF BALL

(75) Inventors: David L. Felker, Escondido, CA (US);
Douglas C. Winfield, Madison, AL (US)

(73) Assignee: Aero-X Golf, Inc., Escondido, CA (US)

() Term: 14 Years

(21) Appl. No.: 29/364,360

(22) Filed: Jun. 22, 2010

(51) LOC (9) Cl. 21-02

(52) U.S. Cl. D21/709

(58) Field of Classification Search D21/707-714;
473/351-385

See application file for complete search history.
